Primary Examiner — Kevin K. Rudzinski

Reexamination Request:

No. 90/019,349, Dec. 22, 2023

Reexamination Certificate for:

Patent No.: **Des. 1,002,985**
Issued: **Oct. 24, 2023**

EX PARTE
REEXAMINATION CERTIFICATE

NO AMENDMENTS HAVE BEEN MADE TO 5
THE PATENT

AS A RESULT OF REEXAMINATION, IT HAS BEEN
DETERMINED THAT:

The patentability of claim 1 is confirmed. 10
